UNITED STATES PATENT OFFICE.

NORRIS BULL, OF ROCHESTER, NEW YORK.

DESIGN FOR A CLOSURE FOR PHOTOGRAPHIC-PLATE HOLDERS.

SPECIFICATION forming part of Design No. 31,814, dated November 7, 1899.

Application filed August 14, 1899. Serial No. 727,221. Term of patent 7 years.

To all whom it may concern:

Be it known that I, NORRIS BULL, a citizen of the United States, residing at Rochester, in the county of Monroe and State of New York, have invented and produced a new and original Design for Closures for Photographic-Plate Holders, of which the following is a specification, reference being had to the accompanying drawings, forming a part thereof, in which—

Figure 1 is a perspective view of my improved closure. Fig. 2 is a transverse section of the same.

As shown in the drawings, the leading or material features of my design consist of an elongated rectangular plate or base B, upon which are arranged a series of ribs A, arranged parallel to each other and projecting out-

ward from the flat base at an angle thereto, leaving a longitudinal groove between the 26 ribs. This article is adapted to be placed near the outer end of a photographic-plate holder to act as a light-excluder.

Having described my invention, what I claim as new, and desire to secure by Letters 25 Patent of the United States, is—

The design for a closure for photographic-plate holders, as herein shown and described.

In testimony whereof I have signed my name to this specification in the presence of 30 two subscribing witnesses.

NORRIS BULL.
